UNITED STATES PATENT OFFICE.

MORTON G. BUNNELL, OF CHICAGO, ILLINOIS, ASSIGNOR, BY MESNE ASSIGNMENTS, TO WESTERN WHEELED SCRAPER COMPANY, OF AURORA, ILLINOIS, A CORPORATION OF ILLINOIS.

ROAD-SCRAPER.

SPECIFICATION forming part of Letters Patent No. 739,383, dated September 22, 1903.

Application filed April 5, 1901. Serial No. 54,460. (No model.)

To all whom it may concern:

Be it known that I, MORTON G. BUNNELL, a citizen of the United States, residing at Chicago, county of Cook, and State of Illinois, have invented a certain new and useful Improvement in Road-Scrapers, of which the following is a specification.

My invention relates to a construction of road-scraper involving an adjustable scraper-blade suspended from a frame or body supported upon front and rear vehicle-wheels.

Objects of my invention are to secure direct draft for the scraper-blade, to prevent tilting or wabbling on the part of the body-frame, to simplify and improve the mechanism for adjusting the scraper-blade and also for adjusting the body sidewise upon the long rear axle, to permit free tilting of the front axle in turning around, and to provide certain details and features of improvement tending to increase the general efficiency and to render a machine of this character satisfactory and serviceable.

To the foregoing and other useful ends the turn-table which supports the blade may have a direct connection with the evener, the arrangement being preferably in the nature of a jointed connection between the goose-neck and the hammer-strap. In this way the pull of the blade is communicated directly to the draft appliances. The king-bolt can pass through the said connection, and with such arrangement the draft connection between the blade and evener sustains the draft of the vehicle as well. In other words, the team pulls the blade and the draft devices of the latter pull the vehicle which is the reverse of the usual arrangement. Ordinarily the team pulls the vehicle and the draft of the blade is on the vehicle-frame. Furthermore, in my improved construction the forward running-gear is provided with laterally-arranged bearings, which prevent rocking or rolling of the body-frame upon the front axle when the machine is either traveling straight ahead or describing a large circle, but which do not interfere with free tilting of the axle in turning around. In this way the frame is steadied and the forward running-gear relieved of injurious strains.

The various adjustments of the blade and also the adjustment of the frame or body upon the rear axle are accomplished through the medium of suitable worm-gearing. This worm-gearing is of such character as to render the adjusting mechanism self-locking, thereby obviating the necessity of providing additional devices for locking the blade in its various adjustments. The gearing also simplifies the adjustment of the frame or body upon the rear axle and, as in the case of its application to the scraper-blade, makes it unnecessary to provide additional means for locking the said body and axle against relative movement.

The character of my invention, together with other advantages, will hereinafter more fully appear.

In the accompanying drawings, Figure 1 is a side elevation of the road-scraper constructed in accordance with my invention. Fig. 2 is a plan of the same. Fig. 3 is a front elevation of the machine shown in Figs. 1 and 2, and Fig. 4 is a rear elevation of the same. Fig. 5 is a transverse section on line $x-x$ of Fig. 1. Fig. 6 is a plan of the worm-gearing, illustrating its adaptation for raising and lowering the scraper-blade. Fig. 7 shows a modified form of worm-gearing. Fig. 8 is a face view of the novel form of worm shown in Fig. 6. Fig. 9 is an enlarged side elevation of the forward portion of the body-frame and the adjacent portion of the axle.

As thus illustrated my invention comprises the suitably-constructed body-frame A, mounted upon front and rear vehicle-wheels 1 and 2. The said frame can be provided with a driver's seat 3 and a tool-box and foot-board 4. The scraper-blade C is suspended from the frame at a point substantially midway between the front and rear wheels. This scraper-blade is preferably secured to a turn-table D, whereby it can be rotated, and thus adjusted to the proper angle, it being understood that the most efficient action is obtained by turning the blade at an angle, as shown in dotted lines in Fig. 2.

The draft appliances can be of the usual form and may consist of the tongue E and the evener E'. The evener is secured to the

tongue by the usual hammer-strap *e*. In order to secure direct draft for the scraper-blade, the gooseneck *F* may be connected with the hammer-strap by means of links *f*. These links are preferably connected with the king-bolt *f'*, thereby making the latter a part of the connecting medium between the blade and evener. Thus arranged the blade has a jointed connection with the draft appliances. 5 With this arrangement the resistance of the scraper-blade will be communicated directly to the evener, so that the team will pull the blade through the medium of a direct connection rather than through the medium of some portion of the vehicle-frame. With the arrangement shown the draft of the vehicle will be upon the said bolt, the bolt in this way, together with the hammer-strap and evener, sustaining the draft of both the vehicle and scraper-blade. This construction may be modified or varied, if desired, and for this reason I do not limit myself to the construction shown and described. The object of this feature of my invention is to throw 20 the draft of the blade directly upon the team, so as to relieve the body-frame of injurious strains. Broadly considered, therefore, my invention contemplates a road-scaper comprising a blade having a direct connection with the draft appliances.

As previously stated, the forward running-gear is constructed with laterally-arranged bearings *G*. These bearings are, it will be observed, of such character that the body-frame cannot roll or rock upon the axle when the machine is running straight ahead or describing a large circle. Each bearing consists of a beveled or rounded portion *g*, which is secured to the body-frame, and a similarly rounded or beveled portion *g'*, which is secured either directly or indirectly to the front axle. Thus formed and arranged these portions present opposing convex or rounded surfaces, which meet and bear upon each other 35 when the axle occupies a position at right angles or substantially at right angles to the length of the frame. When the axle is skewed, as in turning around, the bearing portions carried by the axle are not in engagement with the bearing portions on the frame, and consequently the axle is at such times free to tilt or rock, so as not to subject the running-gear and frame structure to injurious strains. When the axle is returned 40 to its normal position, the rounded or convex bearing portions of the axle slide readily beneath the bearing portions on the frame. In this way the bearings *G* operate to steady and brace the frame upon the axle, but do not in any way interfere with the movements of the latter—that is to say, do not prevent the axle from tilting or rocking in turning around nor from returning to its normal position at right angles or substantially at right angles to the 45 frame. This feature of my invention is also capable of more or less modification and change, and I do not, therefore, limit myself

to the details or particular arrangements shown and described.

The aforescribed scraper-blade is, as previously stated, supported for adjustment in various directions. Preferably the blade has the aforescribed rotary movement, which is accomplished through the medium of the worm-gearing *H*, the shaft *h*, and the crank-shaft *h'*, which can be connected by the universal joint *h²* with the said shaft *h*. These shafts, it will be observed, extend rearwardly, and the crank *h³* is preferably located within reach of the attendant standing on the rear platform 5. The said worm-gearing consists of the worm *h⁴*, (to be hereinafter more fully described,) which engages the teeth *d* of the turn-table *D*. This turn-table is, as previously explained, mounted for rotary movement, so as to adjust the blade angularly, and in the arrangement shown this adjustment can be accomplished by rotating the shafts *h* and *h'* so as to turn the worm, and thereby cause the teeth on the turn-table to travel or pass across its face. This worm-gearing, as will hereinafter more fully appear, is of such character that its operation not only produces the desired adjustment, but that it when at rest serves as a lock for locking the turn-table against further movement.

For the purpose of providing for an up-and-down movement of the blade, so as to permit the blade to be raised and lowered at will, the end portions of the gooseneck *F* can be connected by hanger-rod *I* with the rocker-arms or bell-cranks *I'*, which are suitably pivoted to some portion of the frame structure. With this arrangement the blade can be raised and lowered by rocking or swinging the said bell-cranks about their points of pivotal connection with the frame.

Any suitable known or approved device or arrangement can be adopted for causing this rocking motion on the part of the bell-crank. Preferably, however, and as a matter of further improvement the said bell-cranks are connected with the hand-wheels *12*, which are mounted at the rear of the machine and which are within reach of the attendant standing on the said platform. The rack-bars *I²* are preferably employed as mediums of connection between said hand-wheels and bell-cranks. The shaft of each hand-wheel is preferably provided with a worm *I³*, similar to that previously described, and the said rack-bars are provided with teeth which engage said worm. This particular application of the worm mechanism is illustrated in Figs. 6 and 7. In these figures the worm is shown as consisting of a cone having its face provided with a spiral thread or web *i*. The teeth on the rack-bar are so formed and arranged as to engage the said thread. When the worm is rotated, it is obvious that the thread will engage the teeth in succession and cause the bar to shift longitudinally. This longitudinal shift or adjustment on the part of the bars will cause

the bell-cranks to rock, and thereby either raise or lower the scraper-blade, according to the direction in which the hand-wheels are turned. The power-transmitting connection thus provided between the hand-wheels and scraper-blade is simple and powerful, and, as in the case of the previous application of this worm mechanism, has the further advantage of being self-locking. The hand-wheels are always in readiness to be turned. When properly adjusted, the bars I^2 are locked against further movement. It is also desirable that the scraper-blade be supported in such manner that it can be readily swung from side to side. To such end the turn-table structure can be connected by means of a rod J with a bar J' , which is adjustably secured to the under side of the body-frame. This bar is adjustable longitudinally, and, being connected with the turn-table structure, will obviously cause the blade to swing to one side or the other, according to the direction in which the bar is adjusted. As in the case of former adjustments, this longitudinal adjustment of the bar can be effected in any suitable or desired manner; but as a matter of further and special improvement the rear edge of said bar is formed with teeth, which are engaged by a worm J^2 , similar to those previously described. This worm is mounted at the forward end of the rearwardly-extending crank-shaft J^3 , and the crank of this shaft is, like the hand-wheels and former crank, accessible from the rear platform. With this arrangement the side shift or adjustment of the blade can be readily accomplished by rotating the shaft J^3 .

In practice and for certain purposes it is desirable to provide for a lateral or side shift of the rear end of the body-frame. To this end the rear axle is preferably of some length and so connected with the body-frame as to permit the latter to shift readily from side to side. In other words, the rear end of the body-frame is free to slide or shift laterally upon the rear axle. This lateral side shift or adjustment on the part of the rear end of the body-frame can be accomplished in any suitable or desired manner. As a matter of special improvement, however, the axle is provided with teeth, and the worm K , similar to those employed for adjusting the blade, is arranged in position to engage said teeth. This worm is mounted at the forward end of the longitudinally and horizontally arranged crank-shaft K' . By rotating this crank-shaft, which is supported in bearings secured to the under side of the platform, the body-frame may be caused to shift or slide sidewise along the axle. The worm, as in its previous applications, constitutes not only a powerful adjusting device, but serves also to lock the body-frame and rear axle against relative movement. This feature, like the other features of my invention, is capable of extensive modification and change, and for this reason I do not limit myself to the exact construc-

tion or arrangement shown and described. It may be stated, however, that the form of worm shown in Fig. 6 is preferable, inasmuch as this form obviates the necessity of employing the bevel-gearing shown in Fig. 7. In fact, with the form shown in Fig. 6 the hand-wheel and worm can, if desired, be mounted without any intermediate gearing or flexible connection whatever between them. In other words, the form of worm device shown in Fig. 6 is preferable, for the reason that it is cheaper and involves but few parts.

With respect to the preferred form of worm-gearing, as shown in Fig. 6, it will be seen that the arrangement and formation are such that the axis of the worm-gear is at an angle to the reciprocating rack. With this arrangement and mode of operation the worm-gearing is easily operated and exceedingly efficient in adjusting the scraper-blade or other part of the machine to which it is applied. As shown in Fig. 6, the hand-wheel has a flexible or universal-joint connection with the worm. It will be understood, however, that this joint can, if desired, be omitted and that the hand-wheel can be rigidly mounted upon the shaft of the worm. In other words, with the arrangement shown in Fig. 6 the axis of the worm extends at an angle to the rack, while in Fig. 7 the axis and rack are parallel.

Thus it will be seen that I provide an exceedingly simple and efficient construction; that I provide a novel and highly-efficient form of adjusting mechanism adapted for use in adjusting the blade and also in adjusting the body-frame upon the long rear axle; that I simplify and improve the draft; that I provide a simple and effective arrangement for preventing a rolling or rocking of the body-frame upon the front axle and for relieving the frame structure from injurious strains. I wish to call attention, however, to the fact that the broad claims for my improved side bearings for the front axle are contained in an application for improvement in running-gear, Serial No. 86,912, filed by me in the Patent Office on December 23, 1901.

What I claim as my invention is—

1. In a road-scraper, the combination of a suitable body-frame, a scraper-blade, rearwardly-extending rack-bars, suitable connection between the forward ends of said rack-bars and the scraper-blade structure, worms mounted and arranged to engage the rear end portions of said rack-bars, the axis of each worm extending at an angle to its allotted rack-bar, and suitable hand-wheels for rotating said worms.

2. In a road-scraper, the combination of a suitably-wheeled body-frame, a scraper-blade, arranged between the front and rear wheels, rearwardly-extending and longitudinally-shifting rack-bars, bell-cranks serving as medium of connection between the forward ends of said bars and the scraper-blade structure, worms mounted and arranged to engage the rear end portions of said rack-bars, and suit-

- able hand-wheels for rotating said worms, so as to shift the rack-bars longitudinally and thereby raise or lower the scraper-blade.
3. In a road-scraper, the combination of a 5 suitably-wheeled vehicle-frame, a turn-table arranged between the front and rear wheels, said turn-table having a circle-iron with internally-arranged teeth, a scraper-blade rigidly secured to said circle-iron, a worm mounted and arranged to engage the teeth on said circle-iron, and means for rotating said worm so as to rotate the circle-iron and vary the angle of the blade.
4. In a road-scraper the combination of a 15 suitably-wheeled body-frame, a turn-table having a circular rack, a scraper-blade rigidly secured to said circular rack, a worm mounted and arranged to engage the teeth on said rack, said worm having its axis extending at an angle to said rack, and a rotatable shaft for rotating said worm, so as to vary the angle of the blade.
5. In a road-scraper, the combination of a 25 suitably-wheeled body-frame, a long rear axle for the rear wheels, the body-frame being shiftable laterally along the length of said axle, and a rack and worm for thus shifting the body-frame upon the said axle, said worm having its axis extending at an angle to the 30 rack.
6. In a road-scraper, the combination of a suitably-wheeled body-frame, a scraper-blade suspended from the body-frame, means for raising and lowering the scraper-blade and 35 changing its angle, a long rear axle for the rear vehicle-wheels, the said body-frame being capable of lateral shift or sliding movement along the length of said axle, a rack rigid with said axle, a rotary member provided with a spiral thread adapted to engage the teeth on said rack, and means for rotating said member, so as to cause the body-frame to shift laterally upon the said axle.
7. In a road-scraper, the combination of a 45 suitably-wheeled body-frame, a scraper-blade, a tongue provided with a hammer-strap, a turn-table, a gooseneck arranged to carry the scraper-blade, upper and lower bolsters for the forward running-gear, a king-bolt extending through said bolsters, a link connecting said king-bolt with said hammer-strap, and a link connecting the king-bolt with said gooseneck.
8. A road-machine, comprising a suitably- 55 wheeled body-frame, a long rear axle for the rear vehicle-wheels, suitable connection between said axle and body-frame, the connection being such that the body-frame can shift or slide laterally on said axle, and a worm arranged to engage teeth on said axle, the said 60 worm being mounted for rotation, so as to cause the body-frame to slide or shift laterally on the axle, substantially as described.
9. In a road-scraper, the combination of a 65 suitably-wheeled body-frame, a scraper-blade arranged between the front and rear wheels, rearwardly-extending and longitudinally- shiftable rack-bars, lifting devices serving as medium of connection between the forward ends of said bars and the scraper-blade structure, worms mounted and arranged to engage the toothed rear end portions of said rack-bars, and suitable hand-wheels for rotating said worms, so as to shift the rack-bars longitudinally and thereby raise or lower the 75 scraper-blade.
10. A road-machine, comprising a suitably-wheeled body-frame, a long rear axle for the rear vehicle-wheels, suitable connection between said axle and body-frame, the connection being such that the body-frame can shift or slide laterally on said axle, and a worm arranged to engage teeth on said axle, the said worm being mounted for rotation, so as to cause the body-frame to slide or shift laterally on the axle, substantially as described.
11. In a road-scraper, the combination of a suitably-wheeled body-frame, a tongue suitably secured to the forward axle, a hammer-strap on said tongue, upper and lower bolsters for the forward running-gear, a king-bolt extending through said bolsters, and suitable connections whereby said king-bolt serves as a medium of connection between the scraper-blade structure and the said hammer-strap.
12. A road-scraper, comprising a suitably-wheeled body-frame, a scraper-blade supported by said body-frame, suitable draft appliances, and links connecting the blade structure with the hammer-strap of said draft appliances, substantially as described.
13. In a road-scraper, the combination of a suitably-wheeled body-frame, a scraper-blade suspended between the front and rear wheels, and laterally-arranged bearings for the forward running-gear, said bearings being adapted to hold the blade at a level with the forward axle when the machine is running straight ahead, but permitting the said axle to tilt freely when turned to an angle with the blade.
14. A road-scraper, comprising a body-frame suitably mounted upon front and rear vehicle-wheels, a scraper-blade suitably supported by said body-frame, the forward running-gear being provided with laterally-arranged bearings which prevent rocking or rolling of the body-frame upon the front axle, when the latter is at right angles with the body-frame, but which permit a free tilting of the axle when the same is turned to one side, substantially as described.
15. In a road-scraper, the combination of a suitably-wheeled body-frame, a blade structure carrying a scraper-blade, a tongue suitably connected with the forward axle, a hammer-strap on said tongue, connections whereby said hammer-strap sustains the draft of the wheeled body-frame, and suitable connections whereby the blade structure also has direct draft from the said hammer-strap.
16. A road-scraper, comprising a suitably-wheeled body-frame, a scraper-blade sup-

ported by said body-frame, and a direct draft connection between the scraper-blade and the hammer-strap of said draft appliances, substantially as described.

5 17. A road-scraper, comprising a body-frame mounted upon front and rear vehicle-wheels, a scraper-blade suitably supported by said body-frame, rounded or convex bearing portions secured to the forward portion of the 10 body-frame, and similarly rounded or convex bearing portions mounted upon the front axle, the bearings on the axle engaging the bearing portions upon the frame, when the axle is at right angles to the latter, but the 15 axle being free to tilt when turned to one side, substantially as described.

18. A road-scraper comprising a suitably-wheeled body-frame, a scraper-blade supported by said body-frame and mounted for vertical adjustment, hand-wheels arranged at the 20 rear of said body-frame, a worm for each wheel, longitudinally-shifting rack-bars engaging said worms, and means for connecting said rack-bars with the blade, the rotation of 25 the hand-wheels operating to raise and lower the blade, substantially as described.

19. In a road-scraper, a suitably-constructed body-frame, front and rear vehicle-wheels, a scraper-blade suitably supported by said 30 body-frame, rounded or beveled bearing portions *g* secured to the body-frame, similarly

rounded or beveled bearing portions *g'* supported by and rigid with the front axle, substantially as and for the purpose described.

20. A road-scraper, comprising a suitably-wheeled body-frame, a scraper-blade supported by said body-frame and arranged for bodily side shift or lateral adjustment, a bar adjustably secured to said body-frame, means for connecting said bar to said blade, a rotary 35 worm arranged to engage teeth on said adjustable bar, the axis of the worm extending at an angle to said bar, and means for rotating said worm, so as to shift or adjust said bar, such adjustment of the bar operating to 40 shift or swing the blade sidewise, substantially as described.

21. A road-scraper, comprising a suitably-wheeled body-frame, a scraper-blade supported by said body-frame and mounted for rotation about a vertical axis, the blade structure being provided with a toothed rack, a worm 50 arranged to engage the teeth of said rack, the axis of said worm extending at an angle to the rack, and means for rotating said worm, 55 so as to turn the blade about its vertical axis, substantially as described.
